UNITED STATES PATENT OFFICE.

LUTHER C. CROWELL, OF NEW YORK, N. Y., ASSIGNOR TO ROBERT HOE,
THEODORE H. MEAD, AND CHARLES W. CARPENTER, OF SAME PLACE.

STAPLE-BINDING DELIVERY MECHANISM FOR PRINTING-MACHINES.

SPECIFICATION forming part of Letters Patent No. 615,259, dated December 6, 1898.

Application filed December 31, 1897. Serial No. 665,171. (No model.)

To all whom it may concern:

Be it known that I, LUTHER C. CROWELL, a citizen of the United States, residing at New York, (Brooklyn,) county of Kings, and State 5 of New York, have invented certain new and useful Improvements in Staple-Binding Delivery Mechanism for Printing-Machines, fully described and represented in the following specification and the accompanying drawings, forming a part of the same.

The present improvements relate in a general sense to that class of stapling mechanism especially adapted for attachment to a web-printing machine to form a part of the delivery mechanism therefor, whereby the plicated material in the form of webs or sheets may be bound together in packs by means of staples set therein during the onward progress of the plicated packs, and thus form a completed 20 product, such as a pamphlet or newspaper whose leaves are bound together in book-like form.

More specifically my invention includes a holder adapted to grip the staple upon a setting-bed after the same has been formed and presented to the bed, and means for operating the holder to bring it to and retract it from its setting position.

My invention further consists in certain 30 features and details of construction, which will be hereinafter described, and pointed out in the claims.

In the drawings annexed hereto and forming a part of this specification, Figure 1 is a front elevation of the delivery of a printing-press embodying my invention, some of the parts being broken away. Fig. 2 is a side elevation of the same, the point of view being indicated by the arrow 2 in Fig. 1. Fig. 3 is a section, on an enlarged scale, showing parts of the mechanism on the line 3 3 of Fig. 2. Fig. 4 is a section, on an enlarged scale, on the line 4 4 of Fig. 3, the point of view being to the left of the line. Fig. 5 is a plan, on a 40 larger scale, of the stapling mechanism, the point of view being indicated by the arrow 5 in Fig. 3; and Figs. 6, 7, and 8 are sectional views, similar to Fig. 3, showing different positions of the parts, Fig. 6 showing the staple 50 as nearly formed, Fig. 7 showing the formed staple placed upon the setting-bed and gripped

there by the holding device or swinging jaw, and Fig. 8 showing the staple as being clenched, the holding device undergoing retraction.

Referring to the drawings, the web or webs of paper *a* are led to the stapling mechanism from any appropriate printing and folding or associating mechanism between the carriers A B, which support the stapling mechanism 60 and which may also carry cutting and folding mechanism, although of course, if preferred, the cutting and folding operations may be performed by other means. The paper may be presented to the stapling mechanism in the form of webs or of sheets. The particular form of such mechanism herein shown, but to which I do not in any way limit myself, is the longitudinal web-folder of my Patent No. 331,280, of which 60 and 70 are 70 the nipping or folding rollers.

The staples in connection with which my present invention is to be used may be formed outside of the machine and merely set in the material by the machine, or they may be 75 formed in the machine itself as well as set. The machine shown herein is of the character which both forms and sets the staples. The mechanism shown is also one in which the staples are set with their legs in a line 80 transverse to the run of the fabric being stapled. It will, however, of course be understood that the invention may be applied to a machine in which the staples are set with their legs in range with said line of movement.

In the machine herein shown, as usual in machines of like character, several separate stapling mechanisms are arranged side by side upon the carrier B. As these mechanisms are precisely alike, it will be understood 90 that the description herein applies to each of them, although the parts are referred to for convenience as in the singular rather than in the plural number.

The wire forming the staples is led from the spool 1 between the feeding-rollers 2 3, which rollers are moved from the worm-wheel 4, and thus passes under the fixed anvil 5 and in front of abutment 6 in manner similar to 100 that described in my Patent No. 510,840 and substantially identical with the manner de-

scribed in my pending application, Serial No. 566,347, filed October 21, 1895. The wire is then severed by a knife of the usual construction (not shown) and is formed by being swept along the eccentrically-curved face of the anvil 5 by the bender or former 7, which is reciprocated in a recess in the carrier by an arm 8, mounted on the rock-shaft 9, provided with a rock-arm 10, operated by a fixed 5 cam 11. Before leaving the anvil the legs of the staple are given a converging inclination by the plates 12 12', as described in my said application, and are then deposited by the retiring bender upon the setting-bed 13, preferably at a point 14, where a groove is adapted 15 to receive them and hold them during the operation of setting. The staple formed in this or any other manner having been placed upon the setting-bed, the device which constitutes 20 my present invention now comes into action to hold the staple in position while it is penetrating the material.

It is obviously necessary that the staple-former 7 should be retracted into its socket 25 when it reaches the point at which the two carriers are nearest in contact, and to prevent interference with the material it is desirable that this movement should not be caused by direct impact with the surface of the opposite 30 carrier, but that the former should be positively withdrawn before such impact is possible. This withdrawal must be so made if contact between the staple-former and the material being stapled is to be avoided as to 35 leave the staple inadequately supported. My present invention consists of means for holding the staple in the position in which its legs may be forced through the material, which means are of such a character and so operated 40 as not to come in contact with the material being stapled. The form of my invention shown in this application, to which, however, I do not limit myself, is that of a swinging jaw 15, mounted on short shaft 16, bolted 45 to the framework of the cylinder between the legs of the bender 7. This jaw is rocked on its shaft by an arm 17, mounted upon a rock-shaft 18, which is provided with a rock-arm 20, carrying a bowl, which is controlled by 50 the overhanging cam 21, fixed to the frame. (See Fig. 2.) This cam is so shaped that as soon as the staple is deposited upon the setting-bed by the retiring staple-former the swinging jaw advances to the position shown 55 in Fig. 7. Its lip passes over the crown of the staple and holds it in the groove in the setting-bed until the legs of the staple have penetrated the material being stapled, and the staple is therefore held in position by the material 60 when the swinging jaw is withdrawn, as appears in Fig. 8, and the clenching of the legs of the staple follows by means of a clenching-die 22, which may be either movable or stationary, and in this case is shown as mounted 65 upon the carrier B. The lip of the jaw 15, which engages the staple, is preferably flat and of about the width of the staple-crown,

so that it effectually prevents buckling of the crown while the staple is being driven.

What I claim is—

1. The combination of a staple-setting bed, means for placing staples upon the bed in position to be driven, a moving jaw, and means for causing said jaw to grip the staples upon the bed and hold them until they penetrate the material being stapled, substantially as described. 70

2. The combination of a fixed staple-setting bed, means for placing staples upon the bed in position to be driven, a swinging jaw, 80 and means for causing said jaw to grip the staples upon the bed and hold them until they penetrate the material being stapled, substantially as described.

3. The combination of a fixed staple-setting bed provided with a groove, means for placing staples upon the bed in position to be driven, a moving jaw, and means for causing said jaw to grip the staples in said groove until they have penetrated the material being stapled, substantially as described. 85

4. The combination of a fixed staple-setting bed provided with a groove, means for placing staples upon the bed in position to be driven, a swinging jaw, and means for causing said jaw to grip the staples in said groove until they have penetrated the material being stapled, substantially as described. 90

5. The combination of a staple-setting bed, means for forming a staple and placing it upon the bed in position to be driven, a moving jaw, means for causing it to advance after the staple has been formed and placed upon the bed and grip the staple to the bed until it has penetrated the material being stapled, and 100 means for causing it to retire thereafter, substantially as described. 105

6. The combination of a staple-setting bed, means for forming a staple and placing it upon the bed in position to be driven, a swinging jaw, means for causing it to advance after the staple has been formed and placed upon the bed and grip the staple to the bed until it has penetrated the material being stapled, and means for causing it to retire thereafter, substantially as described. 110

7. The combination of a rotating carrier, a staple-holding mechanism projecting from the surface of the carrier and adapted to hold the staple with its crown upon a setting-bed at the circumference of the carrier with its legs turned outward, a clenching-surface, means for withdrawing the staple-holding mechanism into the carrier as it approaches the clenching-surface, a moving jaw and means for causing the jaw to grip the staple upon the bed after the withdrawal of the first-mentioned staple-holding mechanism and until the staple penetrates the material being stapled, substantially as described. 120 125

8. The combination of a rotating carrier, a staple-holding mechanism projecting from the surface of the carrier and adapted to hold the staple with its crown upon a setting-bed 130

- at the circumference of the carrier with its legs turned outward, a clenching-surface, means for withdrawing the staple-holding mechanism into the carrier as it approaches 5 the clenching-surface, a swinging jaw, and means for causing the jaw to grip the staple upon the bed after the withdrawal of the first-mentioned staple-holding mechanism and until the staple penetrates the material being 10 stapled, substantially as described.
9. The combination of a rotating carrier, a staple-bending tool, a fixed anvil over the face of which the setting-tool sweeps to form the staple, a setting-bed fixed to the carrier upon 15 which the bending-tool places the staple when formed, and the moving jaw for holding the staple upon the bed until the staple has penetrated the material being stapled, substantially as described.
10. The combination of a rotating carrier, a staple-bending tool, a fixed anvil over the face of which the setting-tool sweeps to form the staple, a setting-bed fixed to the carrier upon which the bending-tool places the staple 20 when formed, and the swinging jaw for holding the staple upon the bed until the staple has penetrated the material being stapled, substantially as described.
11. The combination of a staple-setting 25 bed, means for placing the staple upon the bed in position to be driven with the range of its legs transverse to the run of the material being stapled, and a swinging jaw for holding the staple upon the bed until it has 30 penetrated the material, substantially as described.
12. A rotary carrier having mounted thereon a staple-setting bed, means for placing staples upon the bed in position to be driven, a 35 moving jaw, and means for causing said jaw to grip the staples upon the bed and hold them until they penetrate the material being 40 stapled, substantially as described.
13. A rotary carrier having mounted thereon a staple-setting bed, means for placing staples upon the bed in position to be driven, a swinging jaw, and means for causing said 45 jaw to grip the staples upon the bed and hold them until they penetrate the material being 50 stapled, substantially as described.
14. In a stapling mechanism, the combination of a rotating carrier, a setting-bed and a jaw mounted thereon, means for forming and presenting staples to the bed and a cam fixed to the framework of the machine for operating the jaw to hold the staple upon the bed while being set, substantially as described. 55
15. The combination in a staple forming and setting mechanism, of a carrier rotating to present the staples to the point of insertion, a staple-setting bed fixed with reference to the carrier and provided with a setting-groove, means for placing staples in the groove in position to be driven, a moving jaw, and means for causing said jaw to grip the staples in said groove and hold them until they have penetrated the material being 60 stapled, substantially as described. 65
16. The combination in a staple forming and setting mechanism, of means for feeding plicated material onward past staple-inserting means, a carrier rotating to present the staples to the point of insertion; a staple-setting bed mounted upon the carrier, means for placing staples upon the bed in position to 70 be driven, a moving jaw, and means for causing said jaw to grip the staples upon the bed and hold them until they have penetrated the material being 75 stapled, substantially as described. 80
17. The combination in a staple forming and setting mechanism, of means for feeding plicated material onward past staple-inserting means, a carrier rotating to present the staples at the point of insertion, a staple-setting bed mounted upon the carrier and provided with a groove, means for placing staples in the groove in position to be driven, a moving jaw, and means for causing said jaw to grip the staples in the groove and hold 85 them until they have penetrated the material being 90 stapled, substantially as described. 90

In testimony whereof I have hereunto set my hand in the presence of two subscribing witnesses.

LUTHER C. CROWELL.
